Eugene, Oreg.

Application July 25, 1950, Serial No. 175,744

8 Claims. (Cl. 312—293)

This invention relates to a portable cash and ticket box 15 for use in the selling and collection of tickets and is an improvement upon our United States Patent Number 2,508,283 issued May 16, 1950, and entitled Portable Combination Cash and Ticket Box.

One object of this invention is to provide a portable cash and ticket box which includes a walled tray equipped with a dual function partition separating the tray into separate chambers and providing a grip by which the tray may be lifted from the box.

Another object of our invention is to provide a novel cover for the coin chamber of a portable cash and ticket box, said coin chamber comprising plural pockets, whereby the cover may be moved, selectively, to a position uncovering the chamber or to a position covering the chamber and preventing accidental loss or movement of the 30 coins from one pocket to another.

The handling of money or sale of tickets at school dances, plays, and carnivals and at football, basketball, baseball, and track events is a complex operation requiring speed, accuracy, and dexterity. To promote the efficiency of these operations, we have invented a portable cash and ticket box which combines all those features most desirable in a ticket selling and money handling device. This box is a compact unit capable of ready transport from one location to another without mixing the money or tickets and requiring a minimum of skill to operate. It is provided with a movable tray having a cash and a currency carrier equipped with a cover and a hold-down clip, respectively, so the money will not fall out in transit or blow away when tickets are sold in the open. This tray is spaced from the bottom of the box to define a closed ticket compartment in which one or more rolls of tickets may be mounted on spaced vertical spindles. Large, vertical ticket-dispensing slots lead from this compartment and cooperate with circular follower rings which are slidably carried by each spindle so tickets in a variety of sizes will unroll from the spindles without breaking or becoming tangled. In addition, the hinge between the portable box and the complementary ticket-collecting lid therefor is made separable so that each of these elements may be used alone. Thus, each feature of our invention cooperates with and is complementary to every other feature thereof to increase materially the speed and accuracy of portable money handling and ticket-selling operations.

These and other objects and advantages of our invention will hereinafter be set forth with respect to the accompanying drawings, in which:

Figs. 1 and 2 are front and side views, respectively, showing the assembled cash and ticket unit closed and ready for transport to a point of use;

Fig. 3 is a top view showing the box and complementary lid pivoted into the full open position;

Fig. 4 is a detail view, taken substantially on the line 4—4 of Fig. 3, showing the two-part bent lip construction of the hinge joining the box and lid whereby these

2

parts may be separated when the lid is pivoted into the full open position;

Fig. 5 is a section view, taken substantially on the line 5—5 of Fig. 3, showing the entire unit with two rolls of tickets stored therein and indicating, in dashed outline, the pivoted position of the hinged currency carrier;

Figs. 6 and 7 are related top and bottom views, respectively, showing the open top box per se and indicating the manner in which the ticket follower rings are gravity biased to prevent the ticket rolls from breaking or becoming tangled;

Fig. 8 is a section view of the removable tray showing one species of the lid which covers the coin chamber to retain coins therein during transport;

Fig. 9 is a section view similar to Fig. 8 showing a second species of the lid covering the coin chamber; and

Fig. 10 is a detailed view, taken substantially on the line 10—10 of Fig. 9, showing the flanges pendent from the currency carrier for slidably carrying the species of lid shown in Fig. 9.

Referring to the drawings by reference characters, our portable cash and ticket unit includes a bottom 1 and four side walls 2 arranged to define an open-mouthed box. A complementary lid 3 is removably pivoted on one of the side walls by means of one or more two-part hinges. Each of these hinges includes an arc-like bent lip 4 carried by the lid and arranged removably to encompass a portion of a horizontal rod 5 which is secured to the box (see Fig. 4). Thus, when the lid 3 is pivoted to the full open position and lying in the plane of the bottom portion shown in Fig. 3, each of the lips 4 may be lifted from its companion rod and the lid thereby separated from the open top box. Such separation allows the lid to be put to separate use.

Referring now to Fig. 5, we have therein shown a walled tray 6 removably seated in the open top box on the four corner angles 7. This tray is separated into an open top storage space 8 and a plurality of open top coin chambers or pockets 9 by means of a main vertical partition 10 and the sub-partitions 10a. The partition 10 is best formed from a Z-shaped member to provide a lateral ledge 11 which projects from the partition and overlies a portion of each of the coin chambers 9. The ledge 11 thereby forms a grip by means of which the entire walled tray 6 may be lifted from the open top box.

Overlying the storage space 8 so as to form a hinged lid therefor, we provide a currency carrier 12 having a plurality of stalls 13 for accommodating various denominations of currency. Each stall is provided with a hold-down clip 14 biased, by means of an over center spring device 15, to prevent currency from blowing away in the wind. The currency carrier itself is pivoted on the back wall of the tray 6 by means of a hinge 16. This hinge allows the currency carrier to be pivoted, when desired, by gripping the leading edge 17 and lifting the carrier into the dashed line position shown in Fig. 5. Access may then be had to the storage space 8 wherein additional tickets, cash, checks, and ticket punches may be stored.

One important feature, wherein the unit of our present invention is an improvement over the cash and ticket box of our aforementioned patent, resides in the construction of the removable tray 6 as shown in Figs. 8 and 9. This improvement stems from the fact that our invention has found wide use in the institutional field. Thus, many schools and colleges have found our portable cash and ticket box to be most versatile and to be capable of use either with or without the ticket-selling advantages. For example, the removable tray 6 may be used as a portable cash box in the school cafeteria. When so used, the ticket-selling and collecting features are not required. Some means must be provided, however, to prevent the spilling or intermixing of the coins carried in the coin

pockets or chambers 9 while the tray per se is being transported. The means we have invented to prevent such spilling or intermixing will now be explained and contrasted with the similar means which functions when the entire cash and ticket unit is transported.

Figs. 3 and 5 best illustrate the manner in which a stub compartment 18 having a stub slot 19 and a hinged removal door 20 is formed across the front side of the lid 3. This stub compartment 18 possesses a dual utility. When the lid 3 is separated from the open top box and transported to the entrance gate of an athletic event, the stub compartment 18 is used by the gateman to collect ticket stubs. These stubs are fed through the slot 19 and retained in the compartment for counting at the end of a ticket taking period. On the other hand, when the lid 3 is in the full closed position as shown in Figs. 1 and 2, the stub compartment 18 closely overlies the coin chambers 9 and the front edges of the currency stalls 13. As with our previous invention, this construction allows the assembled unit to be carried by the handles 21 without danger of spilling or intermixing the segregated currency, coins and tickets.

Returning to the use of the walled tray 6 per se, it will be seen that the hold-down clips 14 will effectively prevent the loss of currency yet the construction of Fig. 5 provides no means to prevent the loss of coins from the coin chambers 9. Accordingly, we have invented the two species of coin chamber covers shown in Figs. 8 and 9. In Fig. 8, the cover 22 is pivoted by means of a hinge 23 to the lateral ledge 11. The cover itself is laterally hinged intermediate the edges thereof at 24 to allow the same to be folded into the storage space 8 when not in use. The folded position is shown in dashed outline in Fig. 8. In Fig. 9, the cover 25 is arranged to slide across the top of the ledge 11 to allow access to the coin chambers 9. This sliding motion is accommodated by flanges 26 which are pendent from the bottom of the currency carrier 12 (see Fig. 10). Each species of the cover carries a clip 27 on the leading edge thereof complementary to a flexible detent or hole 28. Thus, the cover may be secured in place covering the coin chambers 9 while the tray is transported to or from a point of use.

A further important feature of our invention resides in the manner by which the walled tray 6 is removably seated in the open top box and spaced from the bottom member 1 thereof to define a closed ticket compartment 29 (see Fig. 5). Within this compartment, one or more vertical spindles 30 are secured to the bottom member 1 and extend upward through the compartment to a point adjacent the bottom of the tray 6. As best shown in Fig. 6, the spindles 30 receive ticket rolls 31 and have, slidably mounted thereon, gravity biased ticket follower rings 32. The ends of the ticket rolls 31 are threaded through the slots 33 formed in the front wall of the box and disposed in the plane defined by the ticket compartment 29. In order to accommodate tickets of various sizes, the slots 33 are made slightly larger than the largest ticket and extend the full height of the compartment 29. We have discovered, however, that tickets of lesser width sometimes accidentally spiral up over the top of the vertical spindles 30 and become tangled or tear. This can be very disconcerting to a ticket seller when a long line of customers must be kept waiting. Accordingly, we have invented a circular follower ring 32 which is slidably carried on each spindle 30 and is of sufficient weight to gravity bias the ticket rolls 31 into their original plane. These follower rings 32 ride on the top of the ticket rolls 31 and hold them down. They may be constructed from any well-known material such as cardboard, plastic, or metal. We prefer the cardboard construction since it reduces materially the cost of fabrication.

In operation, either the entire cash and ticket unit or the walled tray per se may be used. If the former, a ticket-selling operation is involved and two stations are gen-

erally required. These stations include a point of sale where the open top box is located and a gate or door where the lid is located. At the point of sale or prior to the arrival there, rolls of tickets 31 are placed over the spindles 30 and covered by the follower rings 32, currency is arranged in the stalls 13 and held down by the clips 14, and coins in various denominations are arranged in the chambers 9. Initially, the entire unit is transported to the seller's booth or cage while the lid 3 is locked in place over the open top box. The lid itself is later removed from the open top box by pivoting the same to the fully open position and lifting the bent lip 4 vertically upward and away from the horizontal rod 5. The doorman or gatekeeper then takes the lid to the door or gate and collects the tickets as customers are admitted. He deposits the ticket stubs in the compartment 18 so they may later be counted to determine the total attendance. The ticket seller need not worry for fear the rolls of tickets 31 will become tangled or spiral upwardly since the follower rings 32 hold the roll accurately in place. Furthermore, when access is to be had to the ticket rolls, the walled tray 6 may be removed by grasping the lateral ledge 11 and lifting. Access may be had to the storage space 8 by prying, with the fingernails, under the leading edge 17 of the currency carrier 12. The carrier 12 will then pivot about the hinge 16 yet the clips 14 will hold the currency down so it cannot spill out.

When desired, the walled tray 6 may be removed from the open top box and used by itself. If this is done, one of the constructions of Figs. 8 or 9 is preferable since each of these species provides a cover which functions to retain the coins in the chambers 9. Thus, the money handling unit is prepared for use initially by arranging various coins in the chamber 9 and various denominations of currency in the stalls 13. Thereafter, either the cover 22 is pivoted into place or the cover 25 is slipped into place. Either cover may then be secured by means of the clip 27 and flexible detent or hole 28. At the point of use, the cover 22 may be folded back upon itself, out of the way, within the storage space 8 or the cover 25 may be slipped back on the pendent flanges 26 to accomplish the same result. Since the walled tray 6 is removable from the open top box, an entire ticket-selling operation may be speeded up by having one person make change from the tray while another person dispenses tickets from the remainder of the box. When the elements are thus separated, one from another, the ticket follower rings 32 possess an added utility in that they hold the ticket rolls 31 down, prevent their observation by the buying public, and protect the tickets from the elements.

In accord with the objects of our invention, we have provided several cooperative improvements in a portable cash and ticket unit. These improvements include a novel, dual function, partition separating the money and storage tray into separate chambers and providing a grip by which the tray may be lifted from the open top ticket box. They also include a novel cover for the coin chamber, a follower ring for the ticket rolls, and a two-part hinge to allow separate use of the box and lid. Each of these improvements cooperates with and is complementary to the other improvements to produce a compact unit capable of increasing materially the speed and accuracy of portable money handling and ticket-selling operations.

We claim:

1. A portable cash and ticket unit including an elongated open-mouthed bottom member defining a container, a walled tray removably seated in the container and spaced from said bottom member a distance sufficient to define therein a closed ticket compartment, a vertical longitudinal partition separating said tray into a coin chamber and a storage space, a currency carrier pivoted on one wall of said tray in position to overlie and seal said storage space, and a cover joined to said tray, being

movable selectively to one position closely overlying said coin chamber in sealing arrangement therewith or to a retracted position underlying said currency carrier.

2. A portable cash and ticket unit including an elongated open-mouthed bottom member defining a container, a walled tray removably seated in the container and spaced from said bottom member a distance sufficient to define therein a closed ticket compartment, a vertical longitudinal partition separating said tray into a coin chamber and a storage space, a lateral ledge projecting from said partition and overlying a portion of said coin chamber to form a lip by means of which said tray may be lifted from said container, a currency carrier pivoted on one wall of said tray in position to overlie and seal said storage space, and a cover joined to said tray, being movable selectively to one position closely overlying said coin chamber in sealing arrangement therewith or to a retracted position underlying said currency carrier.

3. A portable cash and ticket unit including an elongated open-mouthed bottom member defining a container, a walled tray removably seated in the container and spaced from said bottom member a distance sufficient to define therein a closed ticket compartment, a vertical longitudinal partition separating said tray into a coin chamber and a storage space, a lateral ledge projecting from said partition and overlying a portion of said coin chamber to form a lip by means of which said tray may be lifted from said container, a currency carrier pivoted on one wall of said tray in position to overlie said storage space, and a cover movable selectively to one position closely overlying said coin chamber in sealing arrangement therewith or to a retracted position underlying said currency carrier, said cover being pivotally mounted adjacent said ledge for folding into said retracted position.

4. A portable cash and ticket unit including an elongated open-mouthed bottom member defining a container, a walled tray removably seated in the container and spaced from said bottom member a distance sufficient to define therein a closed ticket compartment, a vertical longitudinal partition separating said tray into a coin chamber and a storage space, a currency carrier pivoted on one wall of said tray in position to overlie said storage space, and a cover movable selectively to one position closely overlying said coin chamber in sealing arrangement therewith or to a retracted position underlying said currency carrier, spaced lateral guides carried upon the underside of said currency carrier, said cover being slidably retractable in said guides.

5. A portable cash and ticket unit including an elongated open-mouthed bottom member defining a container, a walled tray removably seated in the container and spaced from said bottom member a distance sufficient to define therein a closed ticket compartment, a vertical longitudinal partition separating said tray into a coin chamber and a storage space, a currency carrier pivoted on one wall of said tray in position to overlie said storage space, and a cover movable selectively to one position closely overlying said coin chamber in sealing arrangement therewith or to a retracted position underlying said currency carrier, said cover being pivotally mounted adjacent said ledge for folding into said retracted position, the leading edge of said cover carrying a clip, a detent on the tray wall, complementary to said clip for releasably securing the cover in said sealing arrangement.

6. A portable cash and ticket unit including an elongated open-mouthed bottom member defining a container, a walled tray removably seated in the container

and spaced from said bottom member a distance sufficient to define therein a closed ticket compartment, a vertical longitudinal partition separating said tray into a coin chamber and a storage space, a currency carrier pivoted on one wall of said tray in position to overlie said storage space, and a cover movable selectively to one position closely overlying said coin chamber in sealing arrangement therewith or to a retracted position underlying said currency carrier, spaced lateral guides carried upon the underside of said currency carrier, said cover being slidably retractable in said guides, the leading edge of said cover carrying a clip, a detent on the tray wall, complementary to said clip for releasably securing the cover in said sealing arrangement.

10 7. A portable cash and ticket unit including an elongated open-mouthed bottom member defining a container, a walled tray removably seated in the container and spaced from said bottom member a distance sufficient to define therein a closed ticket compartment, a vertical longitudinal partition separating said tray into an open top coin chamber and an open top storage space, a lateral ledge projecting from said partition and overlying a portion of said coin chamber to form a lip by means of which said tray may be lifted from said container, a currency carrier pivoted on one wall of said tray in position to overlie said storage space, and a cover movable selectively to one position closely overlying said coin chamber in sealing arrangement therewith or to a retracted position underlying said currency carrier, said cover being pivotally mounted adjacent said ledge for folding into said retracted position.

20 8. A portable cash and ticket unit including an elongated open-mouthed bottom member defining a container, a walled tray removably seated in the container and spaced from said bottom member a distance sufficient to define therein a closed ticket compartment, a vertical longitudinal partition separating said tray into an open top coin chamber and an open top storage space, a lateral ledge projecting from said partition and overlying a portion of said coin chamber to form a lip by means of which said tray may be lifted from said container, a currency carrier pivoted on one wall of said tray in position to overlie said storage space, and a cover movable selectively to one position closely overlying said coin chamber in sealing arrangement therewith or to a retracted position underlying said currency carrier, spaced lateral guides carried upon the underside of said currency carrier, said cover being slidably retractable in said guides.
